US00D559036S

(12) **United States Design Patent** (10) **Patent No.:** **US D559,036 S**
Hayes et al. (45) **Date of Patent:** **** Jan. 8, 2008**

(54) **SET OF RIBS FOR CONTAINER**

(75) Inventors: **Thomas J. Hayes**, McHenry, IL (US); **Scott D. Brown**, Winthrop Harbor, IL (US); **H. Bernard Kirkland**, Lindenhurst, IL (US); **Richard C. Sweeney, Jr.**, Falmouth, ME (US)

(73) Assignee: **Pactiv Corporation**, Lake Forest, IL (US)

(**) Term: **14 Years**

(21) Appl. No.: **29/253,525**

(22) Filed: **Feb. 7, 2006**

(51) **LOC (8) Cl.** **07-01**

(52) **U.S. Cl.** **D7/396.5; D7/396.4; D7/396.1**

(58) **Field of Classification Search** **D7/213, D7/387, 388, 391, 392, 396.1, 396.2, 511, D7/396.5, 512, 396.6, 532, 524–528, 533–536, D7/588, 667, 585; D9/429, 500, 537, 542; 126/246; 220/8, 545, 565, 574, 592.16, 592.17, 220/703, 710.5, 759; 229/400**

(57) **CLAIM**

The ornamental design for set of ribs for container, as shown and described.

DESCRIPTION

FIG. 1 is a top perspective view of a set of ribs for a container.

FIG. 2 is a top plan view of the set of ribs for container of FIG. 1.

FIG. 3 is a side elevational view of the set of ribs for the container of FIG. 1, the opposite sides being identical; and, FIG. 4 is a bottom plan view of the set of ribs for the container of FIG. 1.

The broken lines in the drawings are for illustrative purposes only and form no part of the claimed design.
